(57) **CLAIM**

The ornamental design for a temperature probe, as shown and described.

DESCRIPTION

FIG. 1 is a perspective of a first embodiment of the complete temperature probe showing my new design;

FIG. 2 is a front view thereof;

FIG. 3 is a left side view thereof, the right side being a mirror image;

FIG. 4 is a top view thereof;

FIG. 5 is a bottom view thereof;

FIG. 6 is a perspective view of the partially assembled first embodiment of the temperature probe;

FIG. 7 is a perspective view of the female portion of the first embodiment of the temperature probe;

FIG. 8 is a front view thereof;

FIG. 9 is a back view thereof;

FIG. 10 is a left side view thereof, the right side being a mirror image;

FIG. 11 is a top view thereof;

FIG. 12 is a bottom view thereof;

FIG. 13 is a perspective view of the male portion of the first embodiment of the temperature probe;

FIG. 14 is a front view thereof;

FIG. 15 is a back view thereof;

FIG. 16 is a left side view thereof, the right side, top side, and bottom side being identical;

FIG. 17 is a perspective of a second embodiment of the complete temperature probe showing my new design;

FIG. 18 is a back view thereof;

FIG. 19 is a left side view thereof, the right side being a mirror image;

FIG. 20 is a top view thereof;

FIG. 21 is a bottom view thereof;

FIG. 22 is a perspective view of the partially assembled second embodiment of the temperature probe;

FIG. 23 is a perspective view of the male portion of the second embodiment of the temperature probe;

FIG. 24 is a front view thereof;

FIG. 25 is a back view thereof;

FIG. 26 is a left side view thereof, the right side being a mirror image;

FIG. 27 is a top view thereof;

FIG. 28 is a bottom view thereof;

FIG. 29 is a perspective view of the female portion of the second embodiment of the temperature probe;

FIG. 30 is a front view thereof;

FIG. 31 is a back view thereof;

FIG. 32 is a left side view thereof, the right side, top side, and bottom side being identical; and,

FIG. 33 is a perspective view of the female portion of the second embodiment of the temperature probe.

The evenly broken lines are for illustrative purposes only and form no part of the claimed design. The unevenly broken lines in the drawings define the bounds of the claim and form no part thereof.
